(57) **CLAIM**

An ornamental design for a shovel blade, as shown and described.

DESCRIPTION

FIG. 1 is a perspective view of the shovel blade of the present design, with the handle and the shaft portion being shown in outline for purposes of environment only and forming no part of the claimed design;

FIG. 2 is a front elevational view thereof;

FIG. 3 is a side elevational view as seen from the left hand side of FIG. 1;

FIG. 4 is an end elevational view as seen from the bottom of FIG. 1;

FIG. 5 is a rear elevational view thereof;

FIG. 6 is a side elevational view as seen from the right hand side of FIG. 1; and,

FIG. 7 is a top view thereof.
